UNITED STATES PATENT OFFICE.

JOHN R. MITCHELL, OF CHICAGO, ILLINOIS. ASSIGNOR TO WILLIAM H. MINER, OF CHAZY, NEW YORK.

RAILWAY DRAFT-RIGGING.

1,316,588.

Specification of Letters Patent. Patented Sept. 23, 1919.

Application filed October 18, 1915. Serial No. 56,477.

To all whom it may concern:

Be it known that I, JOHN R. MITCHELL, a citizen of the United States, residing at Chicago, in the county of Cook and State of Illinois, have invented a certain new and useful Improvement in Railway Draft-Rigging, of which the following is a full, clear, concise, and exact description, reference being had to the accompanying drawings, 10 forming a part of this specification.

This invention relates to improvements in railway draft riggings.

Objects of the invention are to provide an improved draft rigging for railway cars, 15 wherein the expense of stop castings is minimized and a minimum number of keys are employed to connect the links with the followers to thereby minimize the slotting of the draft sills.

20 In the drawings forming a part of this specification, Figure 1 is a longitudinal, sectional view of a draft rigging embodying my improvements, the section being taken approximately along the inner face of the 25 draft sill, which would be nearest the observer. Fig. 2 is a horizontal, sectional view of the parts illustrated in Fig. 1 and taken on the line 2—2 thereof, the gear being shown in full buff, and Fig. 3 is a vertical, transverse sectional view taken substantially on the line 3—3 of Fig. 1.

In said drawing, 10—10 denote the draft sills between which extends and is secured thereto, at the rear of the gear, a stop casting 11 which may be of any suitable or desired form. Also secured to the inner faces of the draft members are front stop castings 12—12 with which normally engages a front follower 13. A rear follower 14 is employed, the same having a rearward extension 15 which is normally in engagement with the stop casting 11. The followers 13 and 14 are vertically elongated and have interposed therebetween vertical, twin arranged springs 16—16, the parts being suitably supported by means of a saddle plate 17.

To connect the draw-bar 18 with the followers I employ the following novel arrangement. The rear follower 14, on the 50 sides thereof is provided with recesses 19—19, the latter being flared rearwardly as indicated at 20. Side links 21—21 are employed, each of which has an enlarged rear end 22 which corresponds in shape and 55 size to the flared recess 19. The front fol-

lower 13 is also recessed on its sides, as indicated at 23 to accommodate the links 21, the forward ends of the latter being slotted to receive a coupler key 24 which also extends through the draw-bar, as will be 60 understood. The links 21 are assembled with the rear follower 14 by first placing the rear end of a link to the rear of the follower, then moving the link laterally toward the follower to engage the link in the recess 65 19, and finally drawing the link forwardly relatively to the follower to thereby engage the enlarged end 22 in the enlarged portion of the recess 19.

From the preceding, it will be seen that 70 upon forward movement of the draw-bar and links 21, the rear follower will also be moved forwardly. Under buff, the rear follower will be held stationary by the casting 11 and the springs compressed against it by inward 75 movement of the front follower 13.

As clearly indicated in the drawing, the recesses in the sides of the rear follower are partly covered over by flanges or webs 25, thereby retaining the links in proper position and preventing lateral separation thereof.

From the preceding description, it will be seen that I have provided a detachable connection between the links and the follower 85 which avoids the necessity of transversely extending keys that have heretofore extended through slots in the draft sills, thereby weakening the latter. Also, it will be seen that a relatively small amount of metal 90 is required for the stop castings, thereby decreasing the cost of the parts.

Although I have herein shown and described what I now consider the preferred embodiment of my invention, the same is 95 merely illustrative and I contemplate all changes and modifications as come within the scope of the claims appended hereto, and in particular to all modifications of the detachable connection between the links and the 100 rear follower, of which many forms may be employed.

I claim:

1. In a draft rigging, the combination with a follower having laterally opening recesses on the opposite sides thereof, of links detachably connected to said followers on said sides, each of said links having an enlarged end and said recesses being shaped to correspond to said ends, said follower hav- 110

ing flange portions extending over portions of said recesses and adapted to engage the outer faces of said enlarged ends of the links to prevent the latter from separation laterally from the follower.

2. In a draft rigging, the combination with draft sills, front stop-acting means, rear stop-acting means including an abutment block extending transversely between 10 the sills and having a plain front abutting face, and a draw bar, of yoke-acting means including horizontally extending side members, a transversely extending coupler key detachably connecting said draw bar and the

side members of said yoke-acting means and 15 removable through slots in the sills, shock absorbing means, a front follower, a rear follower cut away on the side edges thereof and provided with laterally projecting horizontal shoulders arranged to support the 20 rear portions of said side members of the yoke-acting means, and transversely extending means passing under and directly supporting said rear follower.

In witness that I claim the foregoing I 25 have hereunto subscribed my name this 4th day of October, 1915.

JOHN R. MITCHELL.
